UNITED STATES PATENT OFFICE.

CHARLES LEA, OF BOSTON, MASSACHUSETTS, ASSIGNOR, BY MESNE ASSIGNMENTS, TO MOHAWK CARPET MILLS, INC., OF AMSTERDAM, NEW YORK, A CORPORATION OF NEW YORK.

CROSS-WEAVING LOOM.

Original application filed November 2, 1916, Serial No. 129,072. Divided and this application filed October 23, 1919. Serial No. 332,782.

To all whom it may concern:

Be it known that I, CHARLES LEA, a citizen of the United States, and a resident of Boston, in the county of Suffolk and State 5 of Massachusetts, have invented an Improvement in Cross-Weaving Looms, of which the following description, in connection with the accompanying drawings, is a specification, like characters on the drawings representing like parts.

This application is a division of my co-pending application Serial No. 129,072, filed November 2, 1916, now Patent No. 1,328,570, dated January 20, 1920, for mechanism for 15 and process of producing chenille.

This invention relates to cross weaving looms particularly adapted for constructing or making chenille. In order that the invention may be clearly understood, I have 20 in the accompanying drawings disclosed one type or embodiment thereof.

In said drawings,—

Fig. 1 is a view partly in side elevation and partly in vertical section of an organized machine for constructing chenille in accordance with my invention;

Fig. 2 is a side elevation thereof;

Fig. 3 is a view of said machine mainly in end elevation, but omitting certain parts 30 of the mechanism disclosed in the application of which this is a division, but not particularly relating to the subject-matter of this application;

Fig. 4 is a detail in side elevation and 35 longitudinal section showing the warp harnesses and the doup harnesses in one position;

Fig. 5 is a similar view, but representing the warp harnesses in another position;

Fig. 6 is a detail mainly in vertical transverse section with parts broken away, and representing means for moving the doup harnesses;

Fig. 7 is a section on the line 7—7, Fig. 45 6, showing one of the cams for imparting lateral or shogging movement to the doup harnesses;

My invention relates to cross weaving looms which may be used for any proper 50 purpose but which are intended more particularly for making chenille. Referring more particularly to the accompanying

drawings, wherein I have represented a single embodiment only of my invention, the framing of the machine is represented generally at 1, it consisting of suitable side uprights connected by tie bars or otherwise. At the back of the machine I support a spool or beam 2 whereon the warp threads 3 are wound and a spool or beam 4 whereon the 55 doup threads are wound. Each of said spools or beams is provided with a brake or tension strap or other means respectively shown at 2', 4'. The warp threads 3 are adapted to be shedded in any suitable manner, and I have herein represented them as 60 extending at a, b respectively through the eyes of needles 6, 7 equal in number to the total number of warp threads 3. The said needles 6 and 7 are carried by the frames 65 8, 9 and at their inner faces are provided with racks 10, 11 meshing with circumferentially formed teeth 12 upon a rock shaft, whereby said frames and their needles are 70 oppositely reciprocated in a vertical plane. 75

The doup threads 5 pass over a rod 13, whereby the slack may be taken up. For this purpose any suitable construction may be employed. I have herein represented said rod 13 as mounted on sleeves, one of which 80 is indicated at 14 and positioned for vertical sliding movement upon upright posts, one of which is indicated at 15 and carried by the frame of the machine. Suitable coil springs, one of which is indicated at 16, are 85 provided yieldingly to support the rod 13 in the position shown in Fig. 1. The doup threads 5 extend through the eyes of needles 17 mounted in and depending from a doup harness frame 18 itself positioned for vertical sliding movement in guideways 19 in the machine frame.

Movements of vertical reciprocation are imparted to the warp harnesses and movements of vertical reciprocation and of transverse or lateral reciprocation are imparted to the doup harnesses in any suitable manner. For this purpose I have represented the following organization of parts, to which, however, I am in no wise limited.

Power may be conveyed to the machine in any suitable manner. Herein for the purpose I have represented the machine as having a drive shaft 20 mounted in suitable

bearings in the machine frame and having a fast thereon a suitable drive pulley and a gear 21. Meshing with the gear 21 is a gear wheel 22 loose on a shaft 23 mounted in 5 suitable bearings in the machine frame. Meshing with the gear 22 is a smaller gear 24 fast on a shaft 25 mounted in the machine frame and having thereon a cam 26 provided with a cam track 27.

10 The gear 22 has in one face thereof a cam track 28 receiving a roll 29 on a lever arm 30 loosely mounted for rocking movement upon the shaft 25 and having pivotally connected at its outer end at 31 a connecting 15 rod 32, which is itself pivotally connected at 33 to the warp heddle frame 9. In this or in any other suitable manner a movement of vertical reciprocation is imparted to the warp heddle frames 8, 9 and sheds are 20 successively formed with the warp threads in a manner not herein necessary more fully to set forth.

In order to impart movements of vertical reciprocation to the doup harness frame, I 25 have herein provided the shaft 34 indicated most clearly in Fig. 6, and have mounted upon the opposite ends thereof crank disks 35, 36 having crank pins 37, 38 receiving the 30 ends of links 39, 40 and of sufficient length to permit slight sliding movement of said links in a direction axially of the said shaft 34. The upper ends of the links 39, 40 are formed as hubs 41, 42 and are suitably connected to the doup harness frame 18. Upon 35 the opposite sides of the frame are provided two cam surfaces 43, 44, which are oppositely positioned and upon which ride the heads of pins 45, 46 suitably tapped into the links 39, 40 about midlength thereof. 40 One of said cam surfaces is indicated more in detail in Fig. 7. Since said cam surfaces are oppositely positioned, the construction and relation of parts are such that in the rocking movement of the shaft 34 preferably 45 through substantially 320° , the doup heddle frame 18 is vertically reciprocated and at the same time is laterally or transversely moved to carry the doup threads across the body of the chenille. Any suitable 50 means may be provided to incorporate the weft with the warp, the weft incorporated means being preferably and herein shown as such as to effect the positioning of separate lengths of weft, to the laying of 55 which, however, my invention is obviously not restricted.

The loom is provided with a reed 47, shown most clearly in Figs. 1 and 4 as fast upon the upper end of a reed frame or lever 60 48, itself loosely mounted for rocking movement upon the shaft 23 and having an arm 49 carrying at its outer end a roll 50 positioned in the cam track 27, whereby said reed is moved to and fro to beat up the weft 65 in a manner not herein necessary more fully

to describe. Carried by said reed 47 is a suitable severing instrumentality for the weft thread, the latter being indicated at 51 in Fig. 4. Herein for the purpose, I have provided two cutting members, the 70 stationary one whereof is indicated at 52 in Fig. 4, and the sliding member whereof is indicated at 53, a spring 54 being secured to the reed to hold said cutting members in cutting relation. The sliding member 53 is 75 prolonged below the reed as indicated at 55 in Fig. 4, and is provided with a roll 56 riding upon a suitable stationary cam 57 upon the frame of the machine and held in engagement therewith by a suitable coil spring 80 58, the construction and relation of parts being such that immediately upon the positioning of the weft length in the shed, said length is severed from the body of the weft. Any suitable means may be provided to present a single weft or any one of a plurality of weft threads to the weft needle or filling carrier. If a plurality of weft threads be employed, they may differ among themselves in color or otherwise. In Fig. 3, I 90 have represented at 59 a portion of a weft magazine having a number of weft thread tubes 60, each of which is adapted to carry a suitable weft thread for presentation to the weft needle or other means for inserting 95 the selected weft thread. The magazine 59, if employed, may be selectively operated in any suitable manner either automatically or manually. Herein for the purpose I have represented the shaft 61 of said magazine as 100 having fast thereon a hand wheel 62 by means of which the desired weft thread may be presented to the weft needle.

The weft needle may be of any suitable character and may be operated in any suitable manner. Herein for the purpose and referring more particularly to Fig. 3, I have represented the weft needle at 63, it being mounted in a bracket itself mounted for sliding movement transversely of the machine upon a guide 65 laterally extending from the machine frame as indicated most clearly in Fig. 3. In order to impart sliding to and fro movement to the weft needle, the bracket 64 thereof has a pin 66 extending through a slot 67 in the upper end of a lever 68 pivoted at 69 upon the machine frame and having a roll 70 received by a groove of the cam 71. The said cam 71 is fast upon the shaft 25.

110 As herein set forth, the fabric that is formed is intended to be cut into narrow strips, technically known as chenille strips. It is wholly impracticable to attempt to form a chenille strip made up of merely straight 115 warps and weft threads, because such a fabric will not hold together. The warp threads will be laterally separated and the fabric or strip wholly disintegrates or comes apart. It is therefore of the greatest importance 120

that doup warp threads be introduced so as transversely to bind the straight warp threads in place. Both the straight warp threads and the doup warp threads cooperate with the needle-like member to introduce the weft threads, because the employment of a shuttle is impractical and would result in a fabric, the weft threads of which would be spaced more or less from each other, a result often termed "grinning".

It is essential to lay the weft threads in such a way that the latter can be very closely compacted, and moreover it is important to provide means whereby a relatively large number of different colored weft threads may be introduced. It would not be practicable to provide a large number of shuttles for this purpose. Therefore the said features clearly cooperate with each other.

Having thus described one illustrative embodiment of my invention, I desire it to be understood that although specific terms are employed, they are used in a generic and descriptive sense, and not for purposes of limitation, the scope of the invention being set forth in the following claims.

Claims:

1. A cross weaving loom comprising in combination, means for interweaving warp and weft threads including a plurality of straight warp harnesses, for introducing a plurality of sets of straight warp threads, a doup harness to present a set of doup warp threads, a rock shaft, gearing thereon engaging the straight warp harnesses, thereby to impart opposite reciprocations to said straight warp harness, and connections from said shaft and cooperating cams to impart reciprocations to said doup harness, and means to introduce weft.

2. A cross weaving loom comprising in combination, means for interweaving warp and weft threads including a plurality of straight warp harnesses, for introducing a plurality of sets of straight warp threads, a doup harness to present a set of doup warp threads, a shaft, gearing thereon engaging the straight warp harnesses, and connections from said shaft to said doup harness, thereby to impart opposite up and down reciprocations to said straight warp harnesses and up and down reciprocations to said doup harness, means to introduce weft, and means to impart lateral movement to said doup harness.

3. A cross weaving loom for making a woven fabric of uniform character from edge to edge adapted to be wholly cut into uniform chenille strips comprising in combination, means to introduce a plurality of sets of straight warps to be shedded, means to present a set of doup warp threads substantially uniformly spaced throughout the width of the fabric for the production of said uniform chenille strips, means to in-

duce in succession throughout the entire width of the fabric a plurality of wefts each of which is disconnected from the precedingly laid wefts, a rock shaft, connections from said rock shaft to impart opposite up and down reciprocations to the harnesses for the straight warps and reciprocations to the harness for the doup warps, and cooperating means to impart lateral movement to said harness for the doup warps.

4. A cross weaving loom comprising in combination, means for interweaving warp and weft threads including a plurality of straight warp harnesses, for introducing a plurality of sets of straight warp threads, a doup harness to present a set of doup warp threads, a shaft, connections from said shaft to impart opposite up and down reciprocations to said straight warp harnesses and also up and down reciprocations to said doup harness, means to introduce a weft, and opposite cams on the machine frame to impart lateral movements to the doup harness.

5. A cross weaving loom comprising in combination, means for interweaving warp and weft threads including a plurality of straight warp harnesses, for introducing a plurality of sets of straight warp threads, a doup harness to present a set of doup warp threads, a shaft, connections from said shaft to impart opposite up and down reciprocations to said straight warp harnesses and also up and down reciprocations to said doup harness, cooperating means laterally to reciprocate the doup harness and a reciprocatory needle to introduce a weft.

6. A cross weaving loom for making a woven fabric of uniform character from edge to edge comprising in combination, means for interweaving warp and weft threads including a plurality of straight warp harnesses for introducing a plurality of sets of straight warp threads, a doup harness to present a set of doup warp threads substantially uniformly spaced throughout the width of the fabric, a shaft, connections from said shaft to impart opposite reciprocations to said straight warp threads, and connections from said shaft, and cooperating means to impart reciprocations both up and down and laterally to said doup harness, a reciprocating member to introduce a weft, and severing means to sever each weft length as laid.

7. A cross weaving loom comprising in combination, means for interweaving warp and weft threads including a plurality of straight warp harnesses for introducing a plurality of sets of straight warp threads, a doup harness to present a set of doup warp threads, a shaft, gearing thereon engaging the straight warp harnesses, thereby to impart up and down reciprocations to said

straight warp harnesses, and means to impart up and down reciprocations to said doup harnesses, and cooperating means including cams 43, 44 to impart transverse movement to said doup harness, and means to introduce weft.

8. A cross weaving loom for making a woven fabric of uniform character from edge to edge comprising in combination, 10 means for weaving warp and weft threads including a plurality of straight warp harnesses for introducing a plurality of sets of straight warp threads, a doup harness to present a set of doup warp threads substantially uniformly spaced throughout the width of the fabric, a shaft, connections from said shaft to impart opposite up and down reciprocations to said straight warp harnesses and up and down reciprocations to 15 said doup harness, and cooperating means laterally to reciprocate the doup harness.

9. Mechanism for forming a fabric of uniform character from edge to edge adapted wholly to be cut into uniform chenille strips comprising in combination, means to 20 introduce a plurality of sets of straight warps to be shedded, means independent of the straight warp introducing means to introduce doup warps substantially uniformly spaced throughout the width of the fabric 25 for the production of said uniform chenille strips and including mechanism independent of the straight warp introducing means laterally to shift said doup warp intro-

ducing means, and means to introduce in succession a plurality of wefts.

10. A cross weaving loom comprising in combination, means for interweaving warp and weft threads including a pair of straight warp harnesses each for introducing a set 40 of straight warp threads, a doup harness to present a set of doup warp threads, a rock shaft, gearing thereon engaging the straight warp harnesses thereby to impart opposite vertical reciprocations to said straight warp 45 harnesses, connections from said shaft to the doup warp harness to impart vertical reciprocations thereto, and cooperating means including opposite cams upon the loom frame to impart lateral movement to 50 said doup harness.

11. A cross weaving loom comprising in combination, means for interweaving warp and weft threads including a pair of straight warp harnesses each for introducing a set of straight warp threads, a doup harness to present a set of doup warp threads, a common rock shaft, operative connections from said shaft to impart vertical reciprocations to the straight warp harnesses and to the 60 doup warp harness, and cooperating opposite cams upon the loom frame simultaneously to impart lateral movement to said doup harness.

In testimony whereof, I have signed my 65 name to this specification.

CHARLES LEA.
